UNITED STATES PATENT OFFICE.

JOHN H. CHERRY AND LOUIS R. MELENDY, OF WATERLOO, IOWA, ASSIGNORS TO THE KELLY MANUFACTURING COMPANY, OF WATERLOO, IOWA.

ROAD-DRAG.

1,073,664.

Specification of Letters Patent. Patented Sept. 23, 1913.

Application filed January 23, 1912. Serial No. 672,838.

To all whom it may concern:

Be it known that we, JOHN H. CHERRY and LOUIS R. MELENDY, citizens of the United States of America, and residents of 5 Waterloo, Blackhawk county, Iowa, have invented certain new and useful Improvements in Road-Drags, of which the following is a specification.

Our invention relates to improvements 10 in road drags, and the object of our improvement is to provide a road drag which is composed of a pair of spaced apart bars or blades, with convenient and suitable means for pivotally connecting them together, and for securing them in such an 15 adjusted position independently, as to permit of either being adjusted to receive either a vertical position or an inclination to the front or rear. This object we have accomplished by the means which are hereinafter 20 described and claimed, and which are illustrated in the accompanying drawings, in which:

Figure 1 is a perspective view of our improved road drag, with a portion of the seat-supporting beam broken away. Fig. 2 is an enlarged transverse section of said road drag, taken on the line *a*—*b* of Fig. 1, looking in the direction of the arrow, and 30 having parts broken away. Fig. 3 is a detail view of a portion of the rear side of the rear blade, showing the pivotal connections therewith and with the intermediate pair of uprights to the middle transverse 35 bar and the rear link to one of the hand levers.

Similar numerals of reference denote corresponding parts throughout the several views.

40 The drag comprises a pair of spaced apart rectangular blades 1 and 2 of like size and form, though the dimensions and form may be varied if desired. Since the stresses upon the blades due to the irregular 45 conformation of the surface traveled over by them will tend to bend or buckle them, we have provided on the rear face of each blade an angle-bar reinforcement, shown at 8 and 9, which are riveted to the blades and 50 render them sufficiently stiff. The blades are pivotally connected together by means of transverse bars 3 and 5 near each end, and an intermediate bar 4, said bars ordinarily lying in a horizontal plane and parallel with each other. These bars are piv-

otally connected to the upper part of the blades by the following means. As shown best in Fig. 3, pairs of uprights 10 and 11, formed of angle-bars, are riveted in a spaced apart relation to the rear faces of 60 said blades 1 and 2, there being a pair near each end of each blade, and an intermediately located pair at the middle of each blade. Said transverse bars are pivoted to said blades by means of the pintle-bolts 27 and 65 31 respectively, at a location above the upper edge of each blade, since the uprights project upwardly above the blades. Said bars may be connected by means of a rod 7 and a beam or plank 12, and a seat may be 70 supported on the latter. In order to adjust the inclinations of the said blades 1 and 2 independently of each other, and then hold them in an adjusted position, we have adopted the following means: The numerals 75 14 and 15 denote hand-levers, both being fulcrumed on a pivot-pintle 29 at a distance above their lower ends to the middle bar 4, and adapted to move past the rack-segments 18 and 19 respectively also supported by said bar 4. Each hand lever has a detent 17 adapted to be projected removably into either of the notches on its adjacent rack-segment, by means of a spring 16 mounted on the lever and connected in a 80 well-known manner to a link 20 and pivoted finger-piece 21, or 22 respectively, whereby the detents may be operated independently of each other. A link 6 has its rear end passed through a slot in the rear blade 1 85 and pivoted on a pintle-bolt 26 to the lower parts of the members 10—11 of the middle pair of uprights. The forward end of said link is pivoted to the lower end of the hand lever 14 on a pivot-pintle 28. Another 90 link 13 has its forward end pivoted on a pivot-pintle 32 between the members 10—11 of the middle pair of uprights secured to the rear face of the front blade 2, while its rear end is pivoted to a pivot-pintle 34 on 95 the lower end of the other hand lever 15. Another link 18 has its forward end pivoted on a pivot-pintle 36 between the members 10—11 of the middle pair of uprights secured to the rear face of the front blade 2, while its rear end is pivoted to a pivot-pintle 38 on 100 the lower end of the other hand lever 15.

A draft-connection 25 may be connected by swivels 24 and 23 to the forwardly-projecting forward ends of the end transverse bars 3 and 5.

105 The hand levers are conveniently located within reach of the operator seated on the seat supported on the beam 12, and may be independently operated as desired to either maintain the blades in a vertical position, 110

or tilt either separately forwardly or rearwardly according to the nature of the surface to be passed over or acted upon and the results desired of either blade. Each 5 blade is therefore permitted three adjustments independent of the other blade, and the drag is thus rendered competent for any variety of function within its scope.

Having described our invention, what we 10 claim as new, and desire to secure by Letters Patent, is:

A road drag, comprising front and rear blades, spaced apart, transverse bars pivotally connected to said blades, abutting oppositely-located hand levers fulcrumed on one of said bars and closely adjacent to 15 each other for either independent or simultaneous operation, a link pivotally con-

nected between the lower end of one hand lever and a part of the front blade below the pivotal connection of said transverse bars to said blade, a link pivotally connected to the lower end of the other hand lever and to a part of the rear blade below the pivotal connection of the said transverse bars to said blade, and means for detachably securing independently either hand lever in an adjusted position.

Signed at Waterloo, Iowa, this 5th day of Jan. 1912.

JOHN H. CHERRY.
LOUIS R. MELENDY.
